UNITED STATES PATENT OFFICE.

JULIAN T. MAYER AND EDMOND LEVIS, OF NEW YORK, AND HERMAN SCHUM, OF BRONX, NEW YORK, ASSIGNEES, BY MEANS ASSIGNMENTS, TO RUDOLPH WURLITZER MFG. CO., OF NORTH TONAWANDA, NEW YORK, A CORPORATION OF NEW YORK.

PIANO.

Application filed May 29, 1922. Serial No. 642,159.

This invention relates to pianos, and more particularly to the novel construction of the metal string plate and of the support for the sound board and associated parts, which obviates all necessity for the part heretofore used, and known as the "piano back."

Objects of our invention are to provide a structure of the character described which is compact in depth so that when it is employed in an ordinary piano, the piano case may be narrower from front to rear than heretofore and so that when employed with automatic playing or reproducing mechanism, the whole may be accommodated in a piano case which is no deeper from front to rear than the case of the ordinary piano; also to provide a structure which gives better musical tone and volume than have been obtainable heretofore, which is cheaper and more economical to manufacture, and which is better adapted to withstand the effects of rough usage and of changes in climatic conditions.

These and other objects and advantages of our invention will be apparent from an examination of the accompanying drawings taken in connection with the following description, of which they form a part. But it will be understood that the particular apparatus shown and described is merely one illustration of our invention, and that many changes within the scope of the appended claims may be made without departing from the invention.

Fig. 1 is a rear view of a piano embodying our invention, a portion of which has been broken away.

Fig. 2 is a vertical section on the line 2—2 of Fig. 1.

Fig. 3 is a vertical section of the same structure on the line 3—3 of Fig. 1.

Referring to the drawings:

1 is the metal string plate appropriately designed and reenforced so as to have sufficient strength to keep the strings, 2, in tension and at the same time to provide the chief support for the sound board, 3, and constitute in and of itself the structural backbone of the piano. For this purpose it is provided with forwardly extending vertical flanges, 13, at each side and with rearwardly extending flanges, 10 and 11, at the sides and bottom of the string plate, and

with a rearwardly extending horizontal flange, 12, opposite the top of the sound board, 3 all preferably cast integral with the string-plate. The flanges, 13, are provided with holes, 14, whereby the string plate, 1, may be rigidly but removably screwed to the side panels, 4, of the piano. The rearward faces 10^a of the flanges, 10, 11 and 12, are preferably so shaped and bevelled that when the sound board, 3, is firmly pressed in position against them, it tends to assume a convex shape on its top or string side and a corresponding concave shape on the bottom or rib side of the soundboard. That is to say, the flanges are preferably so shaped that while, at their intersections, they are substantially in a common vertical plane, intermediate their intersections they are thinner and are preferably bevelled in the direction of their inner edges so that their rearward surfaces lie substantially in a common spherical surface. The resulting tension and permanent crown or dome shape given to the sound board improves the tone of the instrument and gives it enduring musical qualities. Very satisfactory results have been obtained by beveling the faces or seats 10^a at a small angle to the string-plate 1; or in other words, at an angle of about eighty-seven degrees to the horizontal.

The means shown for securing the sound board to the string plate comprise a plurality of channel irons, 5, or angle irons, 6, which are bolted as at 7 through the sound board to the rearward flanges 10, 11, 12 of the string plate. The angle irons, 6, at the sides and bottom of the sound board may also be screwed, as at 8, to the corresponding side panels, 4, and cross beam, 9, respectively of the piano. The rearward flanges of the channel and angle irons, 5, 6, are preferably made narrow so as not to unnecessarily increase the depth of the structure as a whole. They serve to equalize the pressure on the edges of the sound board, 3, between bolts, and they also serve to lock the nuts on the bolts, 7, so that the latter are prevented from loosening up and causing rattle. It will be seen that the size of the nuts corresponds closely to the size of the channel and angle irons so that the nuts are in contact with the rearward flanges

of the said irons and cannot turn. Lock nuts may, of course, be used as an additional precaution.

By these means the sound board is satisfactorily and permanently mounted on the string plate itself and no additional means whatever are necessary or desirable for the purpose. The composite structure comprising string plate, 1, sound board, 3, and channel and angle irons, 5, 6, may be readily assembled without reference to the particular piano case in which it is to be incorporated. It may be built in quantity with standard outside dimensions so that it may be interchangeably fitted in any one of a number of cases or removed from one case to another by simply removing the screws 8 and 14 and applying them in proper position in the new case.

20 We preferably provide the upper channel iron, 5, and the lower angle iron, 6, with vertical holes at convenient locations for the insertion of the packing hooks, 15 and 16. These hooks may be secured to the 25 angle or channel irons by means of nuts, 17, 18, and bolted to the outside of the shipping case by means of the nuts, 19, 20, whereby the entire piano and particularly the delicate sounding devices supported on the 30 string plate are reliably packed for shipment.

Through the use of tuning pins or wrest pins, 21, such as those shown in Letters Patent No. 1,223,412, granted April 24, 1917, 35 to James Alfred Murdock, we are able to dispense entirely with the cumbersome wrest plank or pin block which has heretofore been used.

In the ordinary piano prior to this invention, it has been customary to build up the sound board and string plate structure on a massive timber frame known as the "piano back". The upper part of this "piano back" carried the wrest plank while the lower part constituted a bed for supporting the sound board and through it the string plate. Thus the backbone of the piano was not the string plate as in our present invention but was the heavy timber "piano back"; and except for the screws and bolts supporting the string plate on the "piano back", the whole structure was ordinarily glued together and to the side panels of the piano.

The presence of those glued joints has 55 been a great defect in that it has made pianos sensitive to changes in climatic conditions and to rough handling in shipment; furthermore, it has made necessary so much special work in cutting, joining and fitting in the course of manufacturing individual pianos that large scale "fabrication" of standard size interchangeable parts has not been feasible. Various means for overcoming these difficulties have been suggested but 60 without practical success. Metal backs have

been substituted for the ordinary massive timber frame, but the old defects largely persist or new ones take their places; and furthermore the thickness and bulk of the wrest plank itself have made it impossible 70 to decrease the depth of the piano as a whole even where metal frames were substituted for wood.

In our improved structure we have reversed the old practice by making the metal string plate the backbone and main structural support of the piano instead of providing an additional means for its support. We have thus entirely eliminated both the cumbersome "piano back" and the bulky 75 wrest plank, thereby cutting down materially the depth from front to rear of the sounding mechanism of the piano and providing room for automatic player mechanism in a piano case which is no deeper than 80 that required for the ordinary piano without such mechanism. Our combination of string plate, sound board and means for supporting the sound board under tension on the string plate constitutes an independent 85 self contained unit. It may be incorporated in any desired piano case or changed from one to another without affecting the interrelation of the constituents parts. It 90 is not affected by climatic conditions and it 95 is well adapted to stand hard usage. It makes possible the shipment of the piano in "knock down" form and easy assembly 100 without the exercise of unusual skill. Furthermore our improved piano produces materially better tone qualities not only because of the manner of its construction, but also because by reason of the elimination of the massive timber frame there is nothing 105 in back of the sound board to interfere with the free transmission of the sound waves 110 through the air.

It will be understood that wooden linings, 115 22, 23, may be inserted between the channel or angle irons, 5, 6, and the sound board, 3, or between the sound board, 3, and the rearward flanges, 10, 11, 12, of the string plate, 1, in any well known way in order to obtain the desired strength of tone from the instrument. These linings need not be shaped to give spherical contour to the sound board as has been necessary in the past, because by reason of the shape of the rearward faces 120 of the flanges, 10, 11, 12, the sound board will tend to assume that shape when the bolts, 7, are tightened up whether the linings are used or not. The difficult matter of especially shaping and fitting these linings is avoided by the use of our invention, 125 the same result being obtained through the casting of our metal string plate from a specially designed casting pattern, the plate being afterward milled to standard size and standard shape of rearward flanges. An 130 important advantage of our invention in

this regard is that a predetermined standard tension may be given to the sound board in each piano constructed according to our invention.

5. Having thus described one embodiment of our invention, what we claim as new and desire to secure by Letters Patent is:—

1. In a piano, the combination of a metal string plate and sound-board support, said 10 plate having a beveled crowning seat, a sound-board bearing sidewise along its margin against said seat, the latter extending in the general direction of the plane of the sound-board, and means for clamping said 15 margin to said seat.

2. In a piano, the combination of a metal string plate and sound-board support, said plate having a beveled crowning seat, a sound-board having its marginal portion 20 clamped sidewise against said seat to crown the board and secure it to the string plate, the angle of the crowning seat being approximately eighty-seven degrees, and means for clamping said marginal portion 25 to said seat.

3. In a piano, the combination of a metal string plate and sound-board support hav-

ing beveled crowning flanges extending rearwardly therefrom, a sound-board, and means at the opposite side of said board from said 30 flanges and in registry therewith for uniformly clamping the margin of the sound-board flatwise against the beveled faces of said flanges to hold the sound-board in predetermined standard tension.

35 4. A self-contained, interchangeable sounding mechanism for pianos, comprising a metal string plate and a sound board supported thereon, beveled crowning flanges extending rearwardly from the string plate to 40 the sound board at the periphery thereof, and cooperating devices at the rear of the sound board and in registry with the said flanges to clamp the margin of the sound board flatwise against the beveled faces of 45 the said flanges to hold the sound board in permanent crowned relation to the string plate.

In testimony whereof, we have signed our names to this specification.
